Patented June 29, 1915.

UNITED STATES PATENT OFFICE.

CALEB C. DULA, OF YONKERS, NEW YORK.

TOBACCO PRODUCT.

1,144,823.

Specification of Letters Patent. Patented June 29, 1915.

Application filed March 12, 1915. Serial No. 13,973.

To all whom it may concern:

Be it known that I, CALEB C. DULA, a citizen of the United States, residing at Yonkers, in the county of Westchester and

5 State of New York, have invented new and useful Improvements in Tobacco Products, of which the following is a specification.

My present invention relates generally to tobacco products and more particularly to 10 a characteristically new tobacco stick or roll from which either chewing or smoking charges or both may be cut or otherwise detached when desired; and the invention further relates to a new tobacco package comprising one or more of my improved tobacco sticks or rolls inclosed within a suitable wrapper, envelop or container, the said stick or roll constituting a distinctly new product of manufacture.

20 The prime object of the invention is to provide the consumer with tobacco in an entirely new form, the said new form, which of course includes the general make-up of the product, being more satisfactory in many respects and also more economical, the latter being especially true in the case of a smoking product made according to the invention, all as hereinafter more fully described.

Another object of the invention is to provide a tobacco stick or roll having certain 30 distinctly new features, both as to structural characteristics and shape or form, a preferred form as to shape, size and construction being one that may be conveniently and comfortably carried in the vest or other pocket of the user or in an ordinary cigar case, and from which separate smoking or chewing charges or portions may be readily cut, broken or otherwise detached when desired.

A further object of the invention is to 40 provide a tobacco stick or roll that is substantially free from so-called tobacco "shorts" whereby a clean, free-drawing and otherwise more satisfactory smoke is provided, and wherein smoking sections cut from the roll may be readily inserted directly into an ordinary smoking pipe or tube without the necessity of in any way disturbing or breaking up the form of the cut-off section, it being understood of course that the rolls or sticks, when prepared for smoking purposes, will be made of such a diameter and cross-sectional shape as to 50 more or less closely fit the bowls of smoking pipes or tubes.

Other more or less important objects will

appear from a reading of the detailed description of the invention to follow taken in connection with the following drawing, 60 wherein:

Figure 1, is a perspective view of my improved tobacco stick or roll showing the inclosing and retaining binder. Fig. 2, is a perspective view of one of my improved 65 tobacco rolls or sticks cut or split longitudinally of its length to expose the long-leaf filler. Fig. 3, is a perspective view of one form of wrapped tobacco package made according to the invention. Fig. 4, is a perspective view showing one manner of packing my new product.

Referring to the drawing the reference numeral 10, designates generally one form of tobacco roll or stick made according to 75 the invention, the said roll or stick embodying a filler 12, consisting of a plurality of tobacco leaves or portions of leaves of substantial area superposed and arranged longitudinally of one another and of the stick 80 or roll, the leaves or leaf portions being preferably, but not necessarily, flavored or sweetened in any suitable manner to meet the demands of the trade.

The leaves or portions of leaves constituting the filler 12, are somewhat closely arranged or nested and slightly compacted and shaped into the form of a stick or roll, but not solidly compressed as is the case with the ordinary solid bars or plugs of 90 chewing tobacco now commonly found upon the market, although the density of the filler is preferably slightly greater than the density of a cigar, but not so dense as to prevent a sufficiently free draft for smoking purposes.

The filler 12, is inclosed within a binder 13, preferably consisting of a thin tissue sheet of so-called rice or cigarette paper wrapped about the filler in any suitable 100 manner and secured by means of a pasted or other form of seam 14, the said binder serving to maintain and confine the filler in stick or roll form as originally shaped, but which may be torn away as desired when a chewing 105 portion is required, and which may be readily cut through when a smoking charge is wanted.

I prefer to make my new tobacco rolls or sticks of substantially cylindrical shape and of substantially uniform diameter from end to end, as rolls or sticks of this shape may be comfortably and conveniently carried in the vest or other pocket of the consumer or

in an ordinary cigar case and from which required portions or charges may be readily cut, broken or otherwise detached without waste.

5 While I prefer to make the rolls or sticks of substantially cylindrical form I do not wish to be understood as limiting myself to this particular shape as other shapes may be employed without departing from the spirit of the invention.

10 I prefer to inclose the filler 12, within a thin paper binder 13, as sticks or rolls made in this manner are not only more stable, but they can be manufactured and sold to the consumer very much cheaper than would be the case if leaf-tobacco binders and 15 wrappers, either or both, were employed, because it is a well known fact that tobacco binder or wrapper-leaves must be carefully selected 20 and inspected, as all leaves are not suitable for the purpose, and this inspection and selection of leaves would very materially increase the cost of the product.

25 In preparing the tobacco leaves to form the filler I prefer to first strip the leaves of their stems and then arrange superposed stripped leaf sections longitudinally of one another to provide a filler of the required dimensions, the leaves having been previously 30 treated or conditioned and suitably flavored and sweetened, if a flavored and sweetened product is desired, it being understood that I contemplate making not only a flavored product but also an unflavored or 35 natural leaf product in order to suit the tastes of all consumers. Obviously the 40 filler may be made up of different kinds and grades of tobacco and in this way distinctive blends can be produced. After the rolls or sticks have been formed in the manner described, the ends are preferably cut off square as shown and each roll or stick may then be inclosed within a suitable wrapper, envelop or container 15, which may consist 45 of a sheet of air and moisture proof material, the ends 16 of which, when the latter is formed of glacine or other paper, as shown in Fig. 3 of the drawing, being preferably folded and then secured or pasted in 50 any suitable manner to preserve the tobacco in its original condition for as long a time as possible.

55 Of course I do not wish to be understood as limiting myself to the particular construction of wrapper or envelop herein shown and described, nor do I wish it understood that I am confined to a wrapper or container having only one of my improved tobacco rolls or sticks inclosed therein, as I 60 am aware that other forms of wrappers or containers may be employed without departing from the spirit of the invention, as for instance a container or carton formed as shown in Fig. 4.

Tobacco put up in the form herein de-

scribed has many advantages from the standpoint of the consumer, in that the absence of any appreciable quantity of "shorts" in the roll or the charges cut therefrom, prevents clogging or gumming of the 70 pipe bowl and thus obviates the consequent objectionable odor so characteristic of a foul pipe and which is due to the formation of a soggy "heel" in the pipe resulting from the accumulation of fine particles of tobacco or 75 "shorts" which become saturated with saliva from the mouth of the smoker.

The pipe is more easily and quickly loaded or filled and without loss of any of the tobacco, because a smoking section cut from the roll will retain its cylindrical form and remain intact even though force is required to cause it to enter the pipe bowl. The item of tobacco losses resulting from the filling 80 of pipes with fine-cut, plug-cut, flake and 85 granulated tobaccos, as is well known among pipe smokers, is considerable, and such losses are entirely obviated in my new form of tobacco product.

90 My improved tobacco stick or roll being inclosed and retained in a thin paper binder, is stable and does not flake away or break like an all-tobacco roll, such as a cigar, and by reason of the paper binder smoking or chewing sections or charges of any desired 95 length may be readily cut therefrom without breaking or crushing the stick or roll.

99 Inasmuch as the filler constituting the stick or roll is made up of long-leaf tobacco or portions of leaves of substantial area, arranged longitudinally of one another, and closely confined in roll or stick form, this form, I have found from experience, remains intact while being smoked, not only as to the tobacco filler but also as to the resulting 105 ash which likewise retains its original roll form and does not swell up and become so loose and fluffy as to fall out of the pipe, as is the case with other forms of smoking tobaccos. This therefore makes a 110 much cleaner smoke.

Another important advantage resulting from the use of a paper binder for the stick or roll resides in the fact that when a charge or section is cut therefrom and smoked in a 115 pipe with the binder thereon, the burning tobacco does not seem to form a "cake" or "crust" within the pipe-bowl as is invariably the case with other forms of smoking tobacco, and pipes in which my improved 120 product is smoked do not become foul and objectionable, but remain sweet and clean.

I am of course aware that chewing tobacco in the form of relatively long and wide bars or plugs has been upon the market 125 for many years, but in every instance, so far as I am aware, the said bars or plugs have always been tightly compacted or closely compressed into solid pieces of considerable length and width, the usual practice being

to subject the plugs or bars to great pressure in a suitable press wherein they are allowed to remain under pressure for many hours after which they are packed under pressure 5 into boxes or caddies. The said compacted or compressed bars or plugs are then cut into short lengths or pieces for convenient use by the consumer.

Chewing and smoking tobacco has also 10 been placed upon the market in what are known as "twist" forms, wherein a tobacco bunch having tapering ends is first folded intermediate its ends and the latter then intertwined, the said "twists" being 15 then packed into boxes, cartons or caddies.

Other forms of chewing and smoking tobacco now generally found upon the market are "fine-cut," "long-cut," "plug-cut" and similar varieties which are usually put up 20 in package form, some of which are in a more or less compressed state and others loosely packed.

My improved tobacco roll or stick is distinguished from all other forms of tobacco 25 products of which I am aware, in that the tobacco leaves or sections of leaves from which the roll or stick is made are not solidly compressed or firmly compacted as in the case of the solid bars or plugs of tobacco 30 usually found upon the market; but to the contrary, the leaves or sections of leaves are more or less closely arranged and confined longitudinally of one another to form a roll or stick of relatively small dimensions 35 and of substantially uniform diameter from end to end, and a characteristic of which is that the finished stick or roll may be compressed to a certain extent by simple pressure of the hand but not so readily as in the 40 case of a cigar; and my improved product is further distinguished from the known forms in that each roll or stick is inclosed within a thin paper binder which serves to retain the tobacco leaves or leaf sections in roll or 45 stick form.

My new tobacco product is also distinguished from ordinary cigars now found on the market, including cigars that are provided with protective paper wrappers 50 wherein the paper wrapper is twisted at its ends, in that all cigars of which I am aware, have, in addition to the tobacco filler, a tobacco leaf binder and also a selected tobacco leaf wrapper which incloses the 55 binder; and is further distinguished in that such cigars usually have a tapered end or ends; whereas my new tobacco product is of substantially uniform diameter from end to end and the paper binder is applied directly to the long leaf filler and retains the 60 same in shape, no leaf tobacco binder or

wrapper being present. I can, therefore, manufacture my product at a fraction of the cost of cigars because of the fact that I dispense entirely with a tobacco leaf binder 65 and wrapper, which, as is well understood, constitutes the major part of the cost of a cigar owing to the difference in the quality of the binder or wrapper as compared with the cost of the filler.

A further distinguishing feature of my new product over an ordinary cigar resides in the fact that the tobacco sticks or rolls made in accordance with my invention are a little more densely compressed than a 75 cigar, the roll being more substantial in this respect, although it is not so densely compressed as to interfere with a free draft therethrough when used for smoking purposes as hereinbefore described.

70

80

What I claim is:

1. As a new article of manufacture, a tobacco stick or roll formed to provide sections for chewing or smoking, comprising a filler made up of superposed long leaf tobacco or portions of leaves of substantial area arranged longitudinally of one another, said filler being suitably shaped and confined within a paper binder, to provide a stick or roll of substantially uniform diameter from end to end.

2. As a new product of manufacture, a tobacco stick or roll formed to provide sections for chewing or smoking purposes, comprising a substantially uniform mass of 95 superposed long-leaf tobacco or portions of leaves of substantial area arranged longitudinally of one another, said mass being slightly compacted and shaped into a cylindrical stick or roll, but not solidly compressed, and a binder of smokable paper wrapped about the stick or roll and having its edges overlapped and secured.

3. As a new product of manufacture, a tobacco package embodying a stick or roll, 105 comprising a filler made up of superposed portions of long-leaf tobacco, said portions being of substantial area and arranged longitudinally of one another, said filler being suitably shaped and confined within a paper binder to provide a stick or roll of substantially uniform diameter from end to end, and a protective envelop or container of substantially air and moisture-proof material inclosing the said stick or roll.

110

In testimony whereof I have hereunto set my hand in presence of two subscribing witnesses.
